Primary Examiner — Susan Bennett Hattan*Assistant Examiner* — Vy Koenig(74) *Attorney, Agent, or Firm* — Marshall, Gerstein & Borun LLP(57) **CLAIM**

The ornamental design for film for packaging production, as shown and described.

DESCRIPTION

The sole FIGURE is a plan view of a film for packaging production, showing the new design.

The broken lines on the periphery of the figure represent boundaries of the claimed design and form no part of the claimed design. The other broken lines represent optional score lines in the film and also form no part of the claimed design.
